UNITED STATES PATENT OFFICE

144,164

DESIGN FOR A TYPEWRITING MACHINE

Henry Dreyfuss, New York, N. Y., assignor to
Royal Typewriter Company, Inc., New York,
N. Y., a corporation of New York

Application August 2, 1945, Serial No. 121,176

Term of patent 14 years

(Cl. D64—11)

To all whom it may concern:

Be it known that I, Henry Dreyfuss, a citizen of the United States, residing at New York, in the county of New York and State of New York, have invented a new, original, and ornamental Design for Typewriting Machine, of which the following is a specification, reference being had to the accompanying drawings, forming part thereof.

Figure 1 is a front, top, and left side perspective view of a typewriting machine, showing my new design.

Figure 2 is a top and left side perspective view thereof.

Figure 3 is a top, back, and left side perspective view thereof.

Figure 4 is a top and front perspective view thereof.

The design appearance of the right side is substantially the same as the design appearance of the left side.

I claim:

The ornamental design for a typewriting machine, as shown and described.

HENRY DREYFUSS.
